UNITED STATES PATENT OFFICE.

DANIEL I. ROWLAND, OF DENVER, COLORADO.

MECHANICAL MOVEMENT FOR WINDMILLS AND THE LIKE.

1,402,966.

Specification of Letters Patent. Patented Jan. 10, 1922.

Application filed December 10, 1920. Serial No. 429,634.

To all whom it may concern:

Be it known that I, DANIEL I. ROWLAND, a citizen of the United States, residing at the city and county of Denver, and State of Colorado, have invented certain new and useful Improvements in Mechanical Movements for Windmills and the like; and I do declare the following to be a full, clear, and exact description of the invention, such as will enable others skilled in the art to which it appertains to make and use the same, reference being had to the accompanying drawings, and to the characters of reference marked thereon, which form a part of this specification.

The object of this invention is to provide efficient means for converting rotary motion into reciprocating motion. The invention is particularly designed for windmills, but is applicable to many other uses, as will appear.

The object is accomplished through the medium of an elongated double-faced rack upon a reciprocating head with which rack a driven pinion meshes, the pinion being adapted to travel entirely around the rack, and on the outside and means being provided for guiding the pinion and maintaining it in mesh with the rack as it travels along both sides and around the ends.

In the drawings:

Figure 1 is an elevation, partly in section, showing the invention applied to a windmill;

Figure 2 is a face view of the reciprocating head, showing a pinion in mesh with the rack;

Figure 3 is a side elevation of the head, showing a portion of the side wall broken away to disclose the rack and pinion.

The drawings show the wheel 10 of a windmill on a shaft 12 carried by a standard 14, which in turn carries a gear case 15 containing gears running in oil mounted upon the shaft 12 and upon a second shaft 16.

The two shafts 12 and 16 are carried in the journals 18 on the standard 14. The gears in the gear casing 15 are provided for the purpose of gearing down, and since they run in oil, little or no attention is required.

Upon the free end of the shaft 16 there is mounted a pinion 20 and also a guide roller 22. These parts extend within a reciprocating head 24 mounted upon a vertically disposed arm 25. The head contains a guide way 26 running around the interior of the same, and upon which the outermost face of

the roller 22 travels. A rack is disposed longitudinally of the head and is composed of series and secured in the back of the head 24, preferably of pins or rods 28, arranged in 60 The outer ends of the rods 28 are mounted in a bar 30. The pinion 20 lies outwardly of into an enlargement in the head 24, while the roller 22, so that its outer side projects 65 roller 22 travels around the guide 26. The pinion 20, when rotated by shaft 16, will travel up one side of the rack 28, around the upper end thereof, down the other side, and around the lower end, the guide 26 causing it to follow this path. Since the shaft 16 is 70 fixed in the bearing 18, this movement causes the head 24 to reciprocate. It will be noted that by this construction a long stroke may be obtained with the rack only a very short distance off the center of the shaft 16. Due to 75 the fact of this short distance off center, much less power is required to produce a given reciprocating stroke than with ordinary types of mechanism for this purpose.

The lower end of the arm 25 is provided 80 with a bearing 32 which receives a pin 34 connecting said arm 25 with a vertically disposed rod 35. The parts 25 and 35 extend downwardly through a turntable 36, upon which the standard 14 is mounted and 85 through a depending hollow extension 38 carried by the turntable 36, which extension has an opening 40 for access to the pin 34. The turntable 36 travels upon a track 42 carried by the windmill framework 44, ball 90 bearings 45 preferably being provided. The rod 35 is guided at its upper end in a guide 46 on the turntable, and adjacent its lower end in a guide 48 at the lower end of the extension 38, whereby the reciprocatory 95 motion is confined to a straight line. A collar 50 is fixed on the lower end of the extension 38 to retain a loose collar 52, which abuts against an annular shoulder 54. Bolts, or other suitable retaining means, 55 are 100 carried on projecting pieces 56 of the framework and engage the collar 52, whereby the lower end of the extension 38 is held in lowermost position, thereby maintaining the turntable 36 upon the track 42. At the 105 lower end of the rod 35, a swivel connection 58 with the main reciprocating shaft 60 is provided. In order to relieve the dead weight of the main shaft 60 when the same is descending, and in order to assist in return 110 of the same when ascending, a plurality of compensating springs 62 are connected with

a plate 64 mounted on the upper end of the shaft 60, the upper ends of said springs being connected with the upper portion of the framework 44.

5 From the foregoing it will be apparent that I have provided efficient means requiring a very small amount of power to produce a long reciprocating stroke.

I claim:

10 A windmill comprising a stationary supporting tower, a circular track on the top of said tower, a turntable rotatably mounted on said track, a downwardly projecting conical extension attached to said turntable, 15 a collar secured non-rotatably to the tower

and engaging the lower end of said conical extension, a second collar engaging said extension and rigidly secured thereto, a reciprocating shaft, a pair of spaced guides for said shaft, a vertically disposed arm pivotally attached to said shaft, a wind wheel rotatably mounted on said turntable, means cooperating with said vertically disposed arm for reciprocating said shaft as the wheels turn, and compensating springs having one end attached to said shaft and the other to said turntable. 20 25

In testimony whereof I affix my signature.

DANIEL I. ROWLAND.
